(57) **CLAIM**

The ornamental design for a carrying case body, as shown and described.

DESCRIPTION

FIG. 1 is a left side elevational view of a carrying case body showing my new design, the right side elevation view being identical thereto;

FIG. 2 is a front elevational view thereof, the rear elevational view being a identical image thereto; and,

FIG. 3 is a top plan view thereof, the bottom plan view being an identical image thereto.

The broken lines within an area bounded by solid lines indicates shading. The other broken lines are for illustrative purposes only and form no part of the claimed design.
